COMBINATION MYRINGOTOMY TUBE INSERTER AND ASPIRATOR

James L. Geraci and David L. Walchle, Cincinnati, Ohio,
assignors to Xomox Corporation, Cincinnati, Ohio

Filed Nov. 17, 1972, Ser. No. 307,581

Term of patent 14 years

Int. Cl. D24—02

U.S. Cl. D83—12 A

FIG. 1 is a perspective view of a combination myringotomy tube inserter and aspirator embodying our new design.

FIG. 2 is a plan view of one side thereof.

FIG. 3 is an elevational view of the opposite side of FIG. 2.

FIG. 4 is a top plan view of FIG. 3.

FIG. 5 is a bottom plan view of FIG. 3.

FIG. 6 is an elevational view of the right end of FIG. 1.

FIG. 7 is an end elevational view of the left end of FIG. 1.

We claim:

The ornamental design for a combination myringotomy tube inserter and aspirator, as shown and described.
